UNITED STATES PATENT OFFICE.

FREDERICK ACKERMANN, OF OAK PARK, ILLINOIS.

INTERNAL-COMBUSTION ENGINE.

1,333,591.

Specification of Letters Patent.

Patented Mar. 9, 1920.

Application filed May 31, 1918. Serial No. 237,601.

To all whom it may concern:

Be it known that I, FREDERICK ACKERMANN, a citizen of the United States, and a resident of Oak Park, in the county of Cook and State of Illinois, have invented a certain new and useful Improvement in Internal-Combustion Engines, of which the following is a specification.

This invention has reference to an improvement in engines of the internal combustion type.

An object of this invention is to provide an engine structure wherein all the burnt gases are withdrawn from the combustion chamber, all back pressure is eliminated, power can be used to the end of the travel of the piston, the intake valve closes earlier than in present types of engines, greater compression may be obtained, a larger combustion chamber is provided, and wherein a lighter gas may be used as there is no burnt gas to contend with.

Another object of this invention is to provide an improved structure of engine in which kerosene and other relatively heavy hydrocarbons may be easily and effectively evaporated; and which embodies a structure which is relatively simple, and is positive in operation.

The above, and various other important objects and advantages of this invention will be in part set forth and in part understood from the following detailed description of the present preferred embodiment, the same being illustrated in the accompanying drawings, wherein:

Figure 1 is a longitudinal section through an internal combustion engine constructed according to the present invention, the section being taken through the engine near one side and showing the operating mechanism for controlling the secondary piston and the exhaust valve carried thereby, the secondary piston being disposed in its lowered position.

Fig. 2 is a similar view taken on a different plane through the engine and showing the intake valve and its mechanism.

Fig. 3 is a view similar to Fig. 1, showing the secondary or auxiliary piston raised.

Fig. 4 is a side elevation of the engine, parts being broken away to show the valve operating mechanism.

Fig. 5 is a top plan view of the engine.

Fig. 6 is an enlarged transverse section

through the engine taken on the line 6—6 of Fig. 2.

Fig. 7 is a detail enlarged side elevation of the secondary or auxiliary piston.

Fig. 8 is a diagrammatic view of the valve 60 operating cams, showing the timing of operation thereof.

Referring to these drawings by numerals, 10 designates a crank case of any suitable construction and which supports the lower 65 end of a cylinder 11. While the present drawings illustrate a single cylinder engine, it is, of course, understood that the engine may comprise any number of cylinders as the parts hereinafter described are merely duplicated for each cylinder.

The crank case 10 houses a crank shaft 12 to which one end of a connecting rod 13 is secured, the other end of the connecting rod being pivoted to a piston 14 of usual construction adapted to reciprocate in the cylinder 11. The upper part of the cylinder 11 is inclosed by a water jacket 15, and is provided at one side with a hollow projection 16 in which is formed an intake chamber 17 leading to the upper part of the cylinder 11 at a point spaced below the top wall thereof. An intake valve 18 is seated in the bottom of the intake chamber 17, and is carried on a stem 19 which extends downward and diverges from the lower end of the cylinder 11. A spring 20 is carried by the rod 19 and bears against a bushing 21 fitted through the bottom of the projection 16 for normally seating the valve 18. A 80 push rod 22 is slidably mounted in a sleeve bearing 23 carried upon the upper end of the crank case 10, the rod 22 projecting into the crank case and carrying a roller 24 adapted to ride upon a cam 25. The cam 25 has a lobe at one side adapted to lift the intake valve 16 upon the intake stroke of the piston 14.

An auxiliary or secondary piston 26, in the form of a disk, is mounted to reciprocate 100 in the upper end of the cylinder 11 and when raised lies above the intake chamber 17. The piston 26, as shown in detail, in Fig. 7, has a hollow upstanding stem 27 slidably engaging through the head 28 of 105 the cylinder, and has at the juncture of the stem with the piston 26 lateral orifices or ports 29 which open into a central port 30 leading through the under side of the piston 26. The piston 26 carries an exhaust valve 110

31 which seats upwardly in the port 30, and has a stem 32 which is slidably mounted in the stem 27 of the piston. A spring 33 surrounds the rod 32 and is seated in the hole 5 low stem 27 between a shoulder therein and a pin or the like on the rod 32. The upper end of the hollow stem 27 has an outstanding annular flange 34 beneath which is disposed a spring 35 housed at its lower end in 10 the head 28 of the cylinder. The spring 35 normally urges the piston 26 upward and the spring 33 normally urges the exhaust valve 31 upward into closed position.

The head 28 of the cylinder is provided 15 with an exhaust chamber 36 surrounding the lower end of the hollow stem 27 and opening into an exhaust port 37 in one side of the head which may be controlled by a normally seated spring pressed valve 38.

20 The head 28 of the cylinder carries a post 39 at one side which extends beyond the stem 27, and upon which are pivoted rocker arms 40 and 41. The rocker arm 40 is in the form of an open frame bearing at one end 25 upon the annular flange 34 and at its other end is connected by pin and slot connection to a hollow push rod 42 which extends downward along one side of the engine and is slidably supported in the projection 16. 30 An inner push rod 43 is mounted in the hollow rod 42 and is movable independently thereof through the same. The inner rod 43 has connection with the inner rocker arm 41 which lies within the rocker arm 40 as 35 clearly shown in Fig. 5.

The cam 25 which controls the operation of the intake valve is supported upon a cam shaft 44 carried within the casing 10 and adapted to turn at half the speed of the 40 crank shaft 12. The shaft 44 is provided with a second cam 45 having an intermediate lobe 46 at one side and lateral lobes 47 spaced substantially 10 degrees behind the intermediate lobe 46, the latter having a 45 cam surface of substantially the same radial height as that of the lobes 47 and extending through an arc of substantially ten degrees. The hollow rod 42 is provided upon its lower end with a pair of rollers 48 adapted 50 to bear against the cams 47, and the inner rod 43 carries an anti-friction roller 49 adapted to ride on the cam 46.

In operation, the cams are so positioned upon the shaft 44 that upon the suction 55 stroke of the piston 14 the piston 26 is raised to augment the suction and insure the complete expansion and evaporation of the hydrocarbon fed through the intake chamber 17. The upper piston 26 is maintained in a raised position during the power 60 and compression strokes. Upon the exhaust stroke, however, the cam 46 first operates the inner push rod 43 and opens the exhaust valve 31, and immediately subsequent the 65 cams 47 force the piston 26 downward while

the valve 31 is maintained open. This downward movement of the piston 26 forms an upper compartment in the combustion chamber through which the burnt gases are forced by the main piston 14 as it rises. 70 The two pistons 14 and 26 are brought into proximity with each other upon the completion of the exhaust stroke so that practically all of the burnt gases are driven from the combustion chamber below the upper piston 26. 75

Immediately the main piston 14 descends on the intake stroke, the valve 31 is closed, the cam 25 opens the intake valve 18, and the piston 26 is raised. This causes an increase 80 in the size of the combustion chamber which increases in a relatively great proportion to the stroke of the main piston and effects the suction in the combustion chamber from the very beginning of the intake stroke of 85 the piston. A relatively large charge is therefore drawn into the engine, and the full effect of the power stroke is obtained as no burnt gases are left in the combustion chamber. 90

As the piston 26 rises, and as the valve 31 is closed at this time, the exhaust gases in the upper end of the cylinder 11 are forced out through the port 37 and past the valve 38. Thus, any back pressure in the exhaust 95 can not be communicated to the combustion chamber as the valves are immediately closed and the upper piston 26 increases the tendency to create a vacuum as well as immediately closing communication between the cylinder 100 and the exhaust.

What is claimed is:

1. In an internal combustion engine, the combination of a cylinder, a piston traveling in the cylinder, a second auxiliary piston 105 also traveling in the cylinder and having an exhaust port and a valve seat therein, a valve carried by the auxiliary piston and arranged to move toward and from said seat, a hollow rod carrying the auxiliary piston 110 and fitted to reciprocate in the cylinder, spring means engaging between the rod and cylinder to yieldingly raise the auxiliary piston, spring means within the hollow rod acting to keep the valve on its seat, a pivoted 115 striker comprising an open rectangular frame adapted to come in contact with the rod for depressing the auxiliary piston, a second striker mounted on the same pivot with the first striker and operating within 120 the open rectangular frame constituting the first striker for engaging the valve stem and moving the valve off its seat, a tubular rod for actuating said first striker, a second rod within the tubular rod for actuating the second striker, and successively acting cams for moving said tubular and other rod. 125

2. In an internal combustion engine, the combination of a cylinder having a piston 130 therein, a second auxiliary piston in the cyl-

- inder having an exhaust port and a valve seat therein, a piston rod reciprocating in the cylinder and carrying said auxiliary piston, said rod having an out-turned flange on its upper end, a spring confined between the flange and cylinder for yielding lifting the piston rod, a valve carried by the auxiliary piston, a valve stem connected to the valve and projecting up through the rod, a spring fitted in the rod and connected to the valve stem for yielding raising the valve, a striker composed of an open rectangular frame pivoted on the cylinder and arranged to engage the piston rod, a second striker rocking about the same pivot with the first mentioned 15 striker and operating in said open rectangular frame for engaging the valve stem, a tubular rod connected to the first striker, a rod within the tubular rod for actuating the second striker, and cams for independently 20 lifting said rods.

FREDERICK ACKERMANN.
